UNITED STATES PATENT OFFICE.

EDWARD STILES, OF NEW YORK, N. Y.

RAILWAY.

SPECIFICATION forming part of Letters Patent No. 730,312, dated June 9, 1903.

Application filed September 29, 1902. Serial No. 125,196. (No model.)

To all whom it may concern:

Be it known that I, EDWARD STILES, a citizen of the United States, residing in the borough of the Bronx, in the city and State of New York, have invented a certain new and useful Improvement Relating to Railways, of which the following is a specification.

The improvement relates mainly to the track, but also involves an improvement in the system of conducting the current between the car and electrical connections below.

I will describe the invention as applied to what is commonly known as a "trolley-railroad," having a track so nearly coinciding with the common road that ordinary carriages may use the railroad-track as a part of the road.

I employ an extra rail extending along parallel to the main rail and having a flange at the top which overhangs toward the main rail. This extra rail is set a sufficient distance from the main rail to allow for the passage of the flange of the railway-car wheel between. I provide a shield or cover in short lengths within the continuous slot thus produced, the lengths being pivoted at a lower line in the space and adapted to open laterally by allowing the flanges of the wheels of the car as they extend down below the upper surface of the rails to act in succession in moving the several short lengths of shield under the flange of the extra rail. I have also devised sundry improvements in the details of the track for applying this system and for equipping the wheels of the cars to serve therewith.

The main function of the apparatus is to form an effective and convenient electrical connection between an ordinary feed-wire extending along below and the electric motor. (Not shown on the car.) Another function which may be performed without the main one in many cases is to provide a liberal passage for the travel of the flanges of the wheels along the rail and yet to close such groove immediately the car has passed and hold it closed to exclude dirt and snow and allow carriage-wheels to run on it until the same or another car traverses again in the same or the opposite direction over this part of the track. I will in this specification describe it as adapted to serve both purposes.

The following is a description of what I con-

sider the best means of carrying out the invention.

The accompanying drawings form a part of this specification.

Figure 1 is a plan view of a portion of the track on a small scale. Portions of three shields are shown with the parts in the closed condition ordinarily occupied. Fig. 2 is a cross-section on a sufficient scale to show the details. The strong lines show the shield deflected to one side by the passage of a wheel. The dotted lines show the closed condition. Fig. 3 is a corresponding section of a portion in another position. Fig. 4 is a plan view of one of the springs. Fig. 5 is a cross-section corresponding to Fig. 2, showing a modification. Fig. 6 is a cross-section of a portion of the wheel, showing a modification. Fig. 7 is a section showing a high point in the wheel and the brush in contact therewith.

Similar letters of reference indicate corresponding parts in all the figures where they appear.

There are two separately-rolled rails, each having a lower edge adapted to engage strongly with a common supporting base. One (the main rail) has a tread A, a web A', and a thickened base A², having a deep continuous open slot a² extending its whole length, adapted to match on a support below. This rail carries the load imposed by the car-wheel H in traveling along the line. On the side presented toward the flange of the wheel (the right side in Fig. 1) is a groove a, the purpose of which will appear farther on. Another rail alongside, of equal depth but considerably thinner, has a broad top B overhanging on the side toward the main rail A, the underside of the overhang being of curved outline in cross-section for a purpose which will presently appear. The web of this rail is marked B', and the base is thickened and slotted longitudinally, as indicated by B² b².

I provide a strong base of rolled iron, presenting a broad horizontal portion D, adapted to be well supported on broken stone or other reliable foundation C. The base-piece D and each upright web D' are adapted to engage with the correspondingly-divided bases A² B² of the rails. I apply a small rope F, of fibrous material, or it may be wood-shavings, to form a slightly-elastic layer over the top of each

web D' and secure the rails to the webs by bolts G and nuts G'. The bolts should match the holes loosely, so as to admit of a slight elastic yielding due to the elasticity of the

5 rope F.

The wheel H, which is one of the supporting-wheels of the car and has a flange H' of about the ordinary size and shape, is equipped with a continuous circular contact piece or 10 ring H², which is connected by a suitable contact-brush I above with the electric engine carried on the car. The engine may be any 15 form of electric motor adapted for railroad-car service.

15 On the inner face of each rail A are brazed or otherwise secured at intervals stout brackets A³, each having a horizontal pin A⁴ cast therein. These pins form strong supports for the forked base of the rocking shield now 20 to be described.

M is what I will term a "shield," of which there are a succession in short lengths running the whole length of the track, each mounted on the pins A⁴ by means of forks 25 M⁴, which extend from vertical webs M'. Each shield receives a strong lateral force, urging it to the left in Fig. 1, from the tension of springs to be described farther on. The top M is of sufficient width to extend nearly across 30 between the adjacent faces of the heads A and B of the two rails. Each shield is so adjusted that as it turns on the pins A⁴ the upper surface runs near but not in contact with the under surface of the corresponding 35 head or overhanging part B of the extra rail. The top of each shield is narrowed at each end on the side which is presented toward the rail A to allow the flange H' of the wheel H as it rapidly traverses along the line to easily 40 engage the shield and force it away from the rail-head A. During the passage of each wheel the contact-ring H² on the wheel is brought into electrical union with the contact-piece O on the shield, and a current flows 45 freely from the feed-wire W upward to give the required strong action to the electric motor carried in the car. After the wheel has moved past the spring throws the shield back to its ordinary upright position. There is a 50 considerable offset B³ on the under side of the top B of the extra rail, which serves as a stop to receive the shield and arrest it if momentum or other force should tend to carry it too far. This is important in preserving from 55 injury the delicate contents of the contact-box to be presently described.

The spring J is composed, as shown, of two flat pieces or plates of steel, properly bent and engaged together and loosely secured to 60 the shield-web M' and the extra rail-web B', with liberty to roll a little as the parts assume different angles, while the shield is forced to one side by the passage of a wheel and allowed to return to its usual position after 65 the wheel has passed. I endeavor to so form and arrange the parts that the spring will exert a nearly-constant force, tending to

bring the shield into the ordinary upright position, pressing against the side of the main rail-tread A. If there is any difference, I 70 prefer that the angle assumed when the shield is most deflected shall be such as to more than balance the increased resilience due to the compression of the spring, and consequently the force pressing the shield toward 75 the main rail shall be greatest when the parts are at rest and least when the wheel is passing. The surface of the shield which is pressed against the rail-head A while the device is idle is the edge of the top M. The 80 surface along a line at a little lower level, pressed against the electrical contact H² on the wheel H while the wheel is passing, is less prominent; but as the shield inclines the 85 top retreats faster, so that the line considerably below, and not the extreme top of the shield, touches the wheel. This portion of the shield is equipped with insulating material N and a metal contact O, both of which extend through a hole in the shield. The 90 contact-strip O, extending the whole length of M, is provided with a lateral arm O'. It is electrically connected to a long coiled wire Q, which hangs loosely and allows for the motion while maintaining an efficient electrical 95 connection to a sliding piece R, mounted in a closely-incasing contact-box B⁴, brazed or otherwise held on the web B'. 100

A feed-cable W of any ordinary or suitable construction extends along in the bottom of the space between the webs D' D' and is connected by branch wires W' with a beveled contact-piece X, fixed within the contact-box, having its upper face inclined to match the corresponding inclined lower face of the sliding contact-piece R. A spring S holds the slide R out of contact under all ordinary conditions, and the contact-box B⁴ protects these important parts from all disturbing influences, the most important of which are mud 110 and snow, which might otherwise destroy the action. At each passage of a car the shield M is turned on its supporting-pins A⁴ until its edge strikes the offset B³. In doing this the web M' is pressed against the arm R' of 115 the slide R and moves the slide against the force of the spring S until the inclined faces of the moving contact R and of the fixed contact X are brought together and rubbed a little, so as to keep them always bright. As 120 soon as the wheel has passed the shield M M' M⁴ and the slide R R' commence to return to their ordinary positions, and the circuit is again broken and remains open for any period until another wheel passes. 125

I attach importance to the form and proportions of the parts, especially making the upper portion M of the shield of a less breadth than the width of the space between A and B. This allows the shield to be taken out 130 and reinserted.

Modifications may be made without departing from the principle or sacrificing the advantages of the invention. I can vary the

position of the pivots A⁴, making corresponding changes in the other parts. I can support the shield by a bridge-piece extending across between the two webs A' B', and such a bridge may serve an important function as a "distance-piece." Fig. 5 shows such a modification. This figure also shows another arrangement of the spring corresponding to the spring J in the form previously described.

10 In this modification the shield is formed with a projection on the side toward the main rail A suitable to serve for an abutment for the spring at the bottom and the tread of the main rail is overhung, so as to form a square shoulder suitable for an abutment for the spring at the top. In this arrangement the tension of the spring or springs is exerted downward and the spring serves the double function of urging the shield into its proper 15 upright position with the promptness and force required and also holding the shield down reliably in its bearings on the pins A⁴.

Parts of the invention may be used without the whole. In the modification shown in Fig. 5 the contact-box is dispensed with and the contacts are made by two ordinary exposed arms adapted to make contact and also to slide. In this Fig. 5, Z indicates the distance-piece. A# indicates the square-bottomed head of the main rail; J#, the spring or springs; M#, the top of the shield; M'#, the web, and M²# the arm or arms thereon which receive the tension, and R# and X# the contact-pieces.

35 Fig. 6 shows a modification in the provisions for carrying a contact-ring and the insulation thereof on the wheel. In this form the exterior of the contact-ring coincides with the outline of an ordinary wheel, and the 40 wheel thus equipped will work in precisely the same manner as ordinary car-wheels in all situations, including switches and frogs. In this form H# is the wheel; H¹#, the inner face of the flange; H²#, the contact-ring, and H³# the insulation. For this form shown in Fig. 45 I prefer to use for the insulating material what is known in the trade as "non-combustible fiber." Any insulating material may be used for the other forms of the invention.

50 The parts may be kept in place by adapting the contact-ring to make a sufficiently tight grip and shrinking it in place on the wheel.

I claim as my invention—

1. In an electric railway, the main rail A A' A² and a line of pivots A⁴ supported on such rail by means of brackets A³ and an extra rail parallel thereto having a top B ex-

tending inward partly over the dividing-space, in combination with each other and with an intermediate movable shield M made in short 60 lengths each having a web M' and provisions for strongly supporting the lower edge of each length and allowing it to rock on such support, arranged to be moved laterally by the action of the car-wheels and to be promptly 65 returned by other means after the car has passed, the upper surface of the shield being curved and the lower face of the top B curved to correspond to the motion, all substantially as herein specified.

2. In an electric railway, the main rail and an extra rail parallel thereto having a top B extending inward partly over the dividing-space, in combination with each other and with an intermediate movable shield arranged 70 to be moved laterally and to lie partially under such top by the presence of a car, and with provisions as a spring or springs for applying force to move the shield to cover the space after the car has passed, and with an 75 insulated contact-ring carried on the car-wheel, all adapted to serve substantially as herein specified.

3. In an electric railway, the main rail and an extra rail parallel thereto, having a top B extending inward partly over the dividing-space, in combination with each other and with an intermediate movable shield arranged 80 to be moved laterally and to lie partially under such top by the presence of a car, and with the loosely-fitted electrical connections 85 Q and W W' and the contact-box B⁴ and in-closed sliding contacts R and X, all arranged 90 for joint service substantially as herein specified.

4. In a railway-track the foundation C, base D and uprights D' D', in combination with the main rail and an extra rail held at a little distance parallel thereto, and the forked unions of the parts by the engagement of one 100 between two parts of the other, a rope F of twisted fiber inserted in each junction, and the bolts G extended through slightly-larger holes confining the parts with liberty for slight yielding by the elasticity of the packing-rope, all substantially as herein specified. 105

In testimony that I claim the invention above set forth I affix my signature in presence of two witnesses.

EDWARD STILES.
